UNITED STATES PATENT OFFICE

2,251,669

BADMINTON PRACTICE APPARATUS

Federico Flores, Chicago, Ill.

Application February 7, 1939, Serial No. 255,126

1 Claim. (Cl. 124—16)

This invention appertains to new and useful improvements in amusement apparatus and more particularly to a machine for enabling persons to practice badminton singly, thus dispensing with the necessity of having a partner.

The principal object of the present invention is to provide a machine for shooting badminton shuttle cocks in the direction of the person practicing.

Another important object of the invention is to provide a machine for projecting badminton birds, one at a time, and automatically, after the machine has once been set in operation.

Other objects and advantages of the invention will become apparent to the reader of the following specification.

In the drawings—

Figure 1 represents a side elevational view.

Figure 2 is a front elevation.

Figure 3 is a section on the line 3—3 of Figure 1.

Figure 4 is a vertical sectional view taken substantially on a line 4—4 of Figure 3.

Figure 5 is a cross section on the line 5—5 of Figure 4.

Figure 6 is a side elevational view of the spring mechanism and trip means.

Figure 7 is a fragmentary perspective view of the upper portion of the carriage.

Referring to the drawings wherein like numerals designate like parts, it can be seen that the machine consists of a cylindrical case 5 having the rounded off end portion 6. The other end of the case 5 is open and is provided with the upstanding and depending walls 7 and 8 respectively, each provided with outstanding flanges 9 which extend continuously from one wall to the other.

Numerical 10 denotes the carriage for the shuttle cocks and this is in the form of a plate having outstanding frusto-conical shaped bosses 11 over which the shuttle cocks 12 can be disposed in the manner clearly shown in Figure 1. The shuttle cocks will wedge in place on these tapered bosses 11.

As can be seen in Figures 2 and 3, strap members 13 extend inwardly from the channeled flanges 9 and connect to the barrel 14 which extends forwardly from the machine. The barrel 14 is formed with openings 15 in the top and bottom portions thereof sufficiently large to permit the bosses 11 with the shuttle cocks thereon to pass into the barrel. As can be seen in Figures 3 and 4, and also in Figure 7, the carriage 10 is provided with rearwardly extending flanges 16

adapted to ride in grooves in aforesaid flanges 9 and adjacent each of these flanges 16 is a row of rack teeth 17. These rack teeth mesh with gears 18 carried by the crank shaft 19. The crank shaft 19 has the crank 20 to which is connected the pitman 21. This pitman 21 is eccentrically connected as at 22 to the mutilated gear 23. The mutilated gear is stripped of teeth for approximately 120 degrees of its circumference and the toothed portion is engageable with the rack 24 of the slider 25, this slider being provided with depending lugs 26 through which the plunger rod 27 extends. The plunger rod has a collar 28 against which one of the lugs 26 abuts. An upstanding bracket 29 has the coiled compressible spring 30 bearing against the same at one end while the opposite end impinges against the lug 26 adjacent the collar 28.

The plunger rod 27 operates through the guide 31 on the bracket 32 and has the head 33 which is operative through the aligned boss 11 to strike the body of the corresponding badminton shuttle cock to drive the same through the barrel 14 toward the practicing player.

Once this machine is prepared for operation, it will operate to project each of the shuttle cocks and it is to be understood that any number of bosses 11 may be provided on the carriage 10 to accommodate a corresponding number of shuttle cocks.

In setting the machine for operation, the clock mechanism generally referred to by numeral 34 must be wound by the player. The mechanism includes the usual spring 35 and other mechanism such as is found in key-wound clock mechanism. The winding stem is denoted by numeral 36 and has the removable crank handle 37 for operating the same. The drive is from the shaft 36 by way of the gears 38, 39 and 40 to the spring 35 and the spring carries the gear ring 40 on its surrounding cylinder, in driving engagement with the pinion 41. The pinion 41 is on the shaft 42 with the gear 43 and with this gear 43 is engageable the pall 44. The pall 44 has the counter-balancing weight extension 45 and the depending leg 46 which is fulcrumed as at 47 for rocking action. From the lower end of this leg 46 extends the control line 48 which extends to a remote point or to a point where the player can conveniently pull the same and get himself ready for the first shot.

The gear 43 is on the shaft 42 with the aforementioned mutilated gear 23.

As is found in clock mechanisms, the first gear

38 is preferably provided with a spring pressed pawl 49.

It can now be seen, that as the clock mechanism operates after its release, the gear 23 will rotate in the direction of the arrow (see Fig. 4) and after the last tooth of the gear 23 leaves the rack 24, the rack and slider 25 will be released and as the spring 30 has been compressed under this action of the gear 23, the slider will force the rod 27 toward the right in Figure 4 rapidly causing the head 33 to strike the body part of the badminton shuttle cock and drive the same toward the player through the barrel 14.

The gear 23 will continue to rotate, each time feeding the rack 24 rearwardly and compressing the spring 30 and subsequently releasing the rack to permit the plunger rod 27 to move to project another shuttle cock.

The carriage 10 is gradually fed downwardly to bring the bosses and the shuttle cocks carried thereon successively into proper position to be struck by the plunger head 33. Obviously, the action of the gears 18 on the crank shaft 19 and the plunger will be synchronized so that the action of feeding the shuttle cocks into position and driving the same will be coordinated.

It is preferable that some form of tripod such as is generally referred to by numeral 50 in the drawings, be employed for supporting the machine in the desired position.

While the foregoing specification sets forth the invention in specific terms, it is to be understood that numerous changes in the shape, size and materials may be resorted to without departing from the spirit and scope of the invention as claimed hereinafter. Thus I lay no claim for novelty in respect to the specific advancing and striking means shown in the drawings, inasmuch as many equivalent means are well known in the art. All such equivalent means are to be understood as included within the scope of the following claim.

Having described the invention, what is claimed as new is—

15 A device for periodically projecting badminton shuttle cocks comprising in combination a reciprocating striking member, a magazine for shuttle cocks comprising a projectile-supporting plate provided with a series of spaced frusto-conical 20 shuttle cock-receiving projections open at both ends, means for mounting said plate for movement in a transverse path across the path of said striking member, and means for advancing said plate the space of one frusto-conical projection 25 for every stroke of the reciprocating striking member, thereby serially positioning said shuttle cocks in striking position.

FEDERICO FLORES.
